UNITED STATES PATENT OFFICE.

FELICE GILARDINI, OF TURIN, ITALY.

PROCESS AND APPARATUS FOR THE INSTANTANEOUS TANNAGE OF HIDES AND SKINS.

1,363,771.

Specification of Letters Patent. Patented Dec. 28, 1920.

Application filed April 6, 1918. Serial No. 227,050. Renewed November 17, 1920. Serial No. 424,766.

To all whom it may concern:

Be it known that I, FELICE GILARDINI, a subject of the King of Italy, residing at and whose post-office address is 5, via Giannone, 5 Turin, in the Kingdom of Italy, have invented certain new and useful Improvements in Processes and Apparatus for the Instantaneous Tannage of Hides and Skins; and I do hereby declare the following to be a full, 10 clear, and exact description of the invention, such as will enable others skilled in the art to which it appertains to make and use the same, reference being had to the accompanying drawings, and to letters or figures of 15 reference marked thereon, which form a part of this specification.

This invention has for its object a process for the instantaneous tannage of hides and skins, which consists chiefly in causing the 20 tan liquor under pressure to come into contact with both sides of the hide or skin under treatment, or in causing the said liquor to come into contact with one side only of the skin under treatment, while a vacuum is 25 produced simultaneously on the other side. This invention consists moreover in an apparatus for effecting the said process in a few minutes and in an easy and continuous way.

30 This invention is shown by way of example in the annexed drawing.

Figure 1 is a side view of the whole of the machine.

Fig. 2 is a horizontal section on line A.A 35 of Fig. 1.

Fig. 3 represents, on a larger scale, a partial vertical section of the machine.

Fig. 4 shows, also on a larger scale, a 40 partial plan view of the lower stationary plates of the machine.

Fig. 5 is a plan of one of the frames on which the hides to be treated are stretched.

Figs. 6 and 7 are two partial vertical sections of modified forms shown on a larger 45 scale.

Fig. 8 is a detailed view of the automatic closing device of Fig. 7.

This process may be effected, as above said, by causing the tan liquor under pressure 50 to come into contact with both sides of the hide or skin under treatment, and for this purpose I may use a tight closing receptacle or container of any suitable shape having sufficiently strong walls, in which are placed 55 the hides or skins to be treated.

In this container (that may be stationary or oscillating or rotating) the tan liquor is conveyed and maintained under pressure and produces therefore the tannage of the hide in a much shorter time than by using 60 the processes known heretofore, in which the tan liquor acts under the normal pressure, as it penetrates the holes of the hides or 65 skins to be treated and traverses them through their entire thickness in a much easier and quicker way.

In order to further accelerate the operation, I designed the machine, shown in the annexed drawing, which constitutes an important part of this invention. The principle on which said machine is based, consists in causing the hides to be treated to pass successively between pairs of plates divided into a number of compartments connected at the bottom by means of tubes with a collector 70 75 through which the tan liquor under pressure is conveyed.

The compartments of each plate pair are identical and placed opposite to each other, so that when the plates are pressed against 80 each other, after the hide has been placed between them, the tan liquor acts under pressure on a number of skin sections, each corresponding to the opening of said compartment, on both sides of the skin; moreover 85 the compartments of the series of plate pairs are arranged in such a manner that when the hide leaves the last plate pair, all its surface has been submitted to the action of the tan liquor under pressure and is therefore completely tanned.

In the constructional form shown in Figs. 1 to 5, 1 is the machine frame carrying the three successive lower plates 2, 3 and 4, provided with compartments 5, 6 and 7 respectively. The corresponding upper plates 2¹, 3¹, 4¹ (in which are provided the compartments 5¹, 6¹, 7¹ identical and superposed to those of the lower plates) may be displaced vertically along guides provided in the machine frame, in order that the hide may be introduced and secured between the plates. This vertical displacement is obtained, in the form illustrated, by means of screws 15, the lower ends of which engage, in corresponding threaded recesses provided in the rib 14, while their upper ends project through smooth bores in the frame to prevent axial displacement and are fixed in the bevel wheels 16 journaled on the frame 1. 110

The bevel wheels 16 engage with bevel wheels 17 fitted on a shaft 18, which is caused to rotate with the interposition of a suitable gearing 18¹, by means of an electric motor 19.

5 In this constructional form the compartments 5 and 5¹, 6 and 6¹ are square and the compartments 7 and 7¹ circular. Evidently said compartments may be of any form different from that illustrated by way of example, provided that the skin surface be fully submitted to the action of the solution under pressure and be therefore completely tanned when it leaves the last plate pair, 4, 4¹.

15 The tan liquor is conveyed under pressure in the tubes 8 and 8¹ from which through the collectors 9 and 9¹ it reaches the tubes 10 and 10¹ and the several compartments (Fig. 8). The hide 11, after having been 20 placed on a frame 12 and stretched by means of hooked flat strips 13, is introduced between the first plate pair 2, 2¹ (Fig. 2) while the plate 2¹ is maintained raised and the hand operated taps 8^a of known construction 25 with which the tubes 8 and 8¹ must be provided are turned off. Evidently the width of the different plates must be such as to prevent any hide under treatment to escape from the compartment surface of the plates.

30 The plate 2¹ is then lowered as above described, until the hide is well pressed between it and the lower stationary plate 2 (Fig. 3); the tube taps 8^a and 8¹ are then turned on. As the hide is of irregular form, 35 it cannot cover all the compartments of the plates between which it is pressed and the tan liquor would therefore escape freely into the free space between the plates through the compartments which are not covered by the hide (see the compartments on the left side of Fig. 3) and could not therefore be maintained at the required pressure in the other compartments in which it must act 40 on the hide. In order to prevent this inconvenience taking place, it will be sufficient to provide an automatic valve of any known type closing the outlet end of the tubes 10 in the compartments that are not covered by the hide; in the example shown said valve 45 is constituted by a ball 20.

In Fig. 4 I have shown in dotted lines in the successive plates 3 and 4 the parts of the hide surface that have not been treated during the operation effected in the preceding 50 plates; it is evident that the hide leaving the last plate pair 4, 4¹ will be thoroughly tanned.

The tanning of the hide section 11 comprised between the plates 2, 2¹ having been 55 effected in a few minutes, the taps of the tubes 8 and 8¹ are turned off, the plate 2¹ is raised (this latter being guided in order to allow its linear adjustment) until the hide section that has been previously treated will 60 come between the plates 3 and 3¹; a suitable

stop will hold the frame in the exact position. The upper plates are then lowered and a fresh section of the hide is pressed between the plates 2 and 2¹, while the section before treated remains between the plates 3 and 3¹; the valves admitting the solution under pressure in the compartments of said plates are then opened. By a similar operation the frame is again displaced, so that the first section of the hide will come between the plates 4, 4¹, the second section between the plates 2, 2¹ and the tan liquor under pressure will be caused to act in a similar manner. The size of the plates will be suitably chosen, so that each of them comprises one third of the length of the entire hide; thus, when the tan liquor conveyed to the compartments of the plates 4, 4¹ will be caused to act (in this operation all the three plate pairs will work), one third of the hide will be completely tanned and two thirds partly tanned; by effecting then the displacement of the hide to complete the tanning of the second section, the first plate pair will be released and the first third of a fresh hide to be treated (stretched on a frame as above described) will be introduced between them. All parts of the machine will thus work simultaneously and continually giving a high efficiency.

95 The frame may of course be dispensed with and the hide laid between the plates by hand or by any suitable means; it will then be possible to place the plate pairs of the machine close to each other in order to avoid all interruption of the compartments of one pair with regard to those of the preceding or following plate pairs.

This tanning process, as it has been said, consists further in causing the liquor under pressure to act only on one side of the hide, while on the other side a vacuum is simultaneously produced. Thereby a great rapidity of tanning is obtained, as the vacuum produced on one side of the hide draws the tan liquor, that acts simultaneously under pressure on the other side of the hide through its pores.

The process forming the object of the invention may be very well carried on by the above described machine; it will be sufficient to modify the automatic closing valve of the outlet end of the tubes 10 in the compartments.

In Fig. 6 is represented a modified form of the automatic ball closing device 20 illustrated in Fig. 3; each ball 20 is provided with a seat 21 on the left hand and a seat 22 on the right hand for the lower as well as for the upper plates. In this way the machine will work either by conveying the solution under pressure to the upper part and producing a vacuum at the lower part or by producing a vacuum above and conveying the solution below.

In the modified form shown at Fig. 7, is illustrated a new automatic device for closing the compartments between which there is not the hide and opening those between which the hide is inclosed, when the machine has to work with the solution under pressure in the compartments of the upper plates and a vacuum in the compartments of the lower plates. The device is constituted by a ball 23 that may slide in the chamber 30 and is connected by means of a rod 24 with a smaller lower ball 25, when the upper plates are lowered on the lower ones, the balls 23 (that remain by gravity on their seats 28 disconnecting thus the tubes 10¹ from the corresponding compartments) are raised only in the case that the hide closes the corresponding compartments, this raising action being effected by the hide itself, while where there is not the hide the balls 23 remain on their seats and close by means of the small ball 25 carried by their rod 24, the seats 29 connecting the lower compartments with the suction pipes 10. By opening the tap of the solution under pressure and that of the suction pipes the balls 23 and 25 will remain on their seats, thus insuring a tight closure, while the seats will remain fully opened where the hide is interposed between the compartments.

In order to insure the closure of the seats 29 for hides of any thickness, I may use the arrangement shown in Fig. 8, in which the rod 24 may slide in a flange 26 of the ball 23 and is under the action of a spring 27.

What I claim is:

1. The method of tanning hides which comprises protecting portions of the hide and simultaneously tanning the unprotected portions thereof, exposing the previously protected portions and tanning the same.

2. The method of tanning hides which comprises isolating portions of the hide and subjecting such portions to a tanning solution, and subsequently tanning the untanned portions.

3. An apparatus for tanning hides, comprising clamping plates having recesses in their opposing faces forming compartments for the reception of portions of the hides, said compartments being arranged to successively receive different portions of the hide during its movement through the apparatus.

4. An apparatus for tanning hides, comprising a plurality of pairs of clamping plates having recesses in their opposing faces forming compartments for the reception of portions of the hide, the compartments of one pair of plates being arranged in staggered relation to the compartments of an adjacent pair of plates for the purpose specified.

5. An apparatus for tanning hides, comprising a plurality of pairs of clamping plates having recesses in their opposing faces forming compartments for the reception of portions of the hide, the compartments of one pair of plates being out of longitudinal alignment with the compartments of an adjacent pair of plates, whereby different longitudinal portions of a hide may be tanned simultaneously.

6. In an apparatus for tanning hides, a pair of plates, each plate having a plurality of compartments coöperating to form a series of separate chambers for containing portions of the hide, means for supplying a tanning solution to said chambers, and means brought into operation by the presence of hide in the chambers for controlling the operation of said supplying means.

7. In an apparatus for tanning hides, a pair of plates, each plate having a plurality of compartments coöperating to form a series of separate chambers for containing portions of the hide, means for supplying a tanning solution to said chambers on one side of the hide, means for creating a vacuum in said chambers on the other side of the hide, and means brought into operation by the presence of hide in the chambers for controlling the operation of the supplying means, and means for creating a vacuum.

8. In an apparatus for tanning hides, a pair of plates, each plate having a plurality of compartments coöperating to form a series of separate chambers for containing portions of the hides, conduits communicating with the compartments, and valves for opening and closing said conduits automatically operated by the closure of the compartments by the hide to open the conduits.

9. In an apparatus for tanning hides, a pair of plates, each plate having a plurality of compartments coöperating to form a series of separate chambers for containing portions of the hide, conduits for supplying a tanning solution to the compartments of one of the plates, means connected with the compartments of the other plate for creating a vacuum, and means brought into operation by the closure of the compartments by the hide whereby the tanning solution is supplied to one side of the hide and a vacuum is created on the other side thereof.

In testimony that I claim the foregoing as my invention, I have signed my name.

FELICE GILARDINI.
